UNITED STATES PATENT OFFICE.

OSKAR MARTIN, OF BERGENFIELD, NEW JERSEY.

FOLDING MAT.

No. 841,263.

Specification of Letters Patent.

Patented Jan. 15, 1907.

Application filed March 7, 1906. Serial No. 304,663.

To all whom it may concern:

Be it known that I, OSKAR MARTIN, a citizen of the United States, residing at Bergenfield, Bergen county, State of New Jersey, have invented new and useful Improvements in Folding Mats, of which the following is a specification.

This invention relates to a foldable mat which is of simple construction, superior to strength, and may be readily taken apart for the purpose of repair.

In the accompanying drawings, Figure 1 is a plan of my improved mat, showing it partly broken away; Fig. 2, an end view thereof; Fig. 3, a section on line 3-3; Fig. 1; Fig. 4, a detail of the joint between rod and rail, and Fig. 5 a detail of the nut.

The mat is composed of a number of elongated links or scrapers 6, made, preferably, of wood and provided near each end with a bore or perforation 7. Through these perforations pass the parallel connecting-rods 8, that string up the links into parallel rows, the links of each row being staggered with those of the adjoining rows.

The ends of rods 8 are threaded, as at 9, Fig. 4, and enter perforations 10 in a series of short side rails 11, each rail being adapted for the attachment of two of the rods. These perforations 10 are enlarged at the surface to form communicating sockets and are here provided with a thread 12. The enlarged portion of each perforation 10 is adapted for the reception of a countersunk nut 13, having an internal thread that engages the thread 9 of rod 8 and an external thread that engages the thread 12 of rail 11. In this way nuts 13

securely connect the rods 8 with the rails 11 and being countersunk are not liable to become accidentally dislodged. If the mat is to be taken apart for the purpose of repair, the nut is removed by a suitable key engaging spanner holes or grooves 14. The two flanking rods 8 of the mat carry tubular sleeves 15 between each pair of links 6.

It will be seen that my improved mat is of simple construction, is readily foldable upon rods 8, and may be easily taken apart.

What I claim is—

A folding mat comprising rows of perforated links, parallel connecting-rods having threaded ends, and rails made up in sections, each section having communicating perforations and sockets, the rods each terminating within the corresponding sockets and free of the walls thereof, the perforations being smooth and the sockets screw-threaded, oppositely-disposed flanking rods connecting the links and end sections at corresponding ends or sides of the mat, sleeves loosely disposed upon the flanking rods between the corresponding links and end sections, and nuts fitted in the sockets having internal threads engaging the rods and external threads engaging the threads of the sockets, the nuts being confined within the outer face of said sections.

Signed by me at Bergenfield, New Jersey, this 5th day of March, 1906.

OSKAR MARTIN.
